CANOPY

Claude W. Ahrens, Grinnell, Iowa

Filed Apr. 8, 1960, Ser. No. 60,094

Term of patent 14 years

(Cl. D13—1)

FIG. 1

Fig. 1 is a perspective view of a canopy showing my new design;

Fig. 2 is a side elevational view thereof, the opposite side having the same appearance; and

Fig. 3 is an end elevational view thereof, the opposite end having the same appearance.

The canopy includes a pair of side pilasters which extend above the roof and which comprise an open framework covered throughout by conventional screening.

I claim:

The ornamental design for a canopy, substantially as shown and described.
